UNITED STATES PATENT OFFICE.

JOHN F. MARTENS, OF CINCINNATI, OHIO, ASSIGNOR TO REDWAY
& BURTON, OF SAME PLACE.

DESIGN FOR A HEATING-STOVE.

SPECIFICATION forming part of Design No. 17,759, dated October 4, 1887.

Application filed August 11, 1887. Serial No. 240,741. Term of patent 3½ years.

To all whom it may concern:

Be it known that I, JOHN F. MARTENS, of Cincinnati, county of Hamilton, and State of Ohio, have invented and produced a new 5 Design for the Ornamentation of Heating-Stoves, which is fully set forth and described in the following specification and accompanying illustration, forming part thereof.

The base is a plate having downwardly-10 curved edges and rounded corners. The corner sections of the curved edges of the base are ornamented with a series of overlapping semicircular figures, *a*. The front section of this edge carries the register and name-plate 15 combined in one piece. At the sides of the name-plate the section is ornamented with a few tendrils, *a'*, incised in the surface.

The legs *B*, which are placed at the corners, are vertical throughout their upper two-thirds, 20 or thereabout, and then curve rapidly outward to form the foot. The upper part of the leg bears a lion's head, *b*, front view in high relief, and at each side of the lion's head, at the edge of the leg, a straight vertical bar, *b'*, 25 with curled ends.

The fire-pot section *C* is ornamented with several rows of overlapping scallops *c*, pointing downward. Each scallop terminates in smaller secondary scallops. Each series of 30 scallops overlaps the series below it. The foot-rail *D* bears on its upper surface the scroll-work *d d'*.

The middle section, *E*, is provided with the flaring ring *E'* at its junction with the fire-pot 35 section. The ring *E'* is decorated with a series of separate figures, *E'*, raised above the surface and representing highly conventionalized leaves. The plain skirting *E''* finishes the ring *E'*. The section *E* bears two rectangular doors, *E'* and *E''*. The door *E'* has a raised beading, *e*, around its edge, and within this beading the background *e'* is roughened, as by stippling. The upper part of the door bears a lion's head, *e''*, front view in high relief. On 40 each side of this lion's head is scroll-work *e''*. The door *E''* has raised beading *e''* around its edge, like the beading around the door *E'*. Within the beading the door is open to receive mica panels, and this opening is partly covered by the scroll-work *e''*, arranged about the vertical bar *e''*.

The outer portion of the top is ornamented with separate scroll figures *f*, similar to each other. Above this zone the top is decorated with a series of concentric rounded rings, *G*, 55 arranged one above the other.

The dome *H* has its edge decorated with parallel vertical lines *h*, and its top with the vine *h'*. The whole is surmounted by the urn *I*. 60

What I claim as new, and desire to secure by Letters Patent, is—

1. In a design for a stove, the ornamentation of the fire-door *E'*, consisting of the beading *e*, background *e'*, lion's head *e''*, and scroll-work *e''*, substantially as shown and described. 65

2. In a design for a stove, the ornamentation of the upper door, *E''*, consisting of the beading *e''*, scroll-work *e''*, and bar *e''*, substantially as shown and described. 70

3. In a design for a stove, the ornamentation of the fire-pot section with series of overlapping scallops *c*, each having secondary scallops, substantially as shown and described. 75

4. In a design for a stove, the configuration 75 of the base and ornamentation thereof with overlapping figures *a* and tendrils *a'*, substantially as shown and described.

5. In a design for a stove, the configuration 80 of the leg and the ornamentation thereof with the lion's head *b* and bars *b'*, substantially as shown and described.

6. In a design for a stove, the ornamentation of the top with the scrolls *f*, rings *G*, lines *h*, vine *h'*, and urn *I*, substantially as 85 shown and described.

7. In a design for a stove, the ornamentation of the top with scrolls *f*, rings *G*, vine *h'*, and urn *I*, of the upper door with scroll-work *e''* and bar *e''*, of the fire-door with background *e'*, lion's head *e''*, and scroll-work *e''*, of the fire-pot section with the series of overlapping scalloped figures *c*, of the base with overlapping figures *a* and tendrils *a'*, and of the feet with the lion's head *b*, all substantially as 95 shown and described.

JOHN F. MARTENS.
